CLAIM

The ornamental design for a set of fork, spoon and knife, as shown and described.

DESCRIPTION

FIG. 1 is a front, bottom and right side perspective view of the spoon of a set of fork, spoon and knife, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, bottom and right side perspective view of a fork thereof;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front, bottom and right side perspective view of a knife thereof;

FIG. 16 is a front view thereof;

FIG. 17 is a rear view thereof;

FIG. 18 is a right side view thereof;

FIG. 19 is a left side view thereof;

FIG. 20 is the enlarged plan of the top view;

FIG. 21 is the enlarged plan of the bottom view; and,

FIG. 22 is a locally enlarged figure of FIG. 1.
